United States Patent Office.

ALMERON GRAVES, OF ROSCOE, ILLINOIS.

Letters Patent No. 74,681, dated February 18, 1868.

IMPROVEMENT IN APPARATUS FOR HANDLING ANIMALS IN SLAUGHTERING.

The Schedule referred to in these Letters Patent and making part of the same.

TO ALL WHOM IT MAY CONCERN:

Be it known that I, ALMERON GRAVES, of Roscoe, in the county of Winnebago, and State of Illinois, have invented certain useful Improvements in Apparatus for Handling Animals in Slaughtering; and I do hereby declare the following to be a full, clear, and exact description thereof, reference being had to the accompanying drawings, and to the letters of reference marked thereon, and making a part of this specification, in which—

Figure 1 is a perspective view of the apparatus.

Figure 2, transverse view thereof.

A, in fig. 1, and A A, in fig. 2, represent two sticks of timber, in which the lower end of the post or upright, B, is fastened. B represents an upright post, fastened at the bottom, as noted above, and secured by rods running from the top thereof, and fastened to the ends of the timbers A A. C D E represent the lever for raising and handling the animals; fulcrum at C, with hook at E. H H H H H, bars securely fastened, by means of iron bolts or pins, to supports, I I I I I I. The supports I I I I I I, for sustaining the bars, are fastened, by means of pins, to iron wheels or revolving caps E E.

Claim.

What I claim as my invention, and desire to secure by Letters Patent, is—

The application of the lever C D E, the upright, B, the revolving apparatus represented by H H H H H, supports I I I I I I, and the revolving caps E E, in apparatus for handling animals in slaughtering.

ALMERON GRAVES.
